LACE CURTAIN AND METHOD OF MANUFACTURING THE SAME

Edgar F. Stiner, New York, N. Y.

Application August 20, 1938, Serial No. 225,907

9 Claims. (Cl. 96—24)

This invention relates to a method of manufacturing Nottingham lace curtains with a fringe forming a part of the pattern along the running or side edge of edges thereof; and to Nottingham lace curtains having a fringe along the running edge thereof woven as a part of the pattern, as a new article of manufacture. This application is a continuation in part of my former application Serial Number 204,939, filed

10 April 29, 1938.

Heretofore fringes for lace curtains have been manufactured separate from the fabrics, on machines other than lace making machines and have thereafter been attached to the lace curtain by sewing. The bullion fringe is one well-known form of fringe thus attached to lace curtains. This arrangement is unsatisfactory because: (a) it is impossible to match either the color or the texture of the fringe with that of the fabric of the lace curtain; (b) applying a fringe to a lace curtain is an additional operation requiring extra handling; and (c) a certain amount of fringe is wasted because the length of the lace curtain to be fringed is invariably different from the length of the fringe itself. My prior application Serial Number 204,939 discloses a method of manufacturing lace fringes generally, and a lace fabric having a fringe woven as a part of the pattern; the said fringe being formed by weaving close network alternating with open structure, between successive warp threads or groups of warp threads, across the width of the lace fabric to form a lace fringe at the top or bottom edge of the lace fabric.

35 One object of this invention is a method of fabricating lace fringes along the running edge of lace piece goods, and more particularly along the running edge of a Nottingham lace curtain. Another object is a method of fabricating lace fringes along the running edge of Nottingham lace curtains, woven upon a Nottingham lace curtain machine, Levers machine, or the like.

40 Another object is lace piece goods, particularly Nottingham lace curtains, having a lace fringe along the side or running edge thereof.

45 Other objects will appear from the detailed description.

In the drawings comprising four sheets of 22 figures numbered Figs. 1 to 22 both inclusive:

50 Fig. 1 is a plan view of a fragment of a lace edging showing the first stage in the development of one form of my lace fringe.

55 Fig. 2 is a plan view of a fragment of another pattern of lace edging from which another embodiment of my lace fringe may be developed.

Fig. 3 is a plan view of a fragment of another pattern of lace edging from which still another embodiment of my lace fringe may be developed.

Fig. 4 is a plan view of a fragment of another pattern of lace edging showing the first stage 5 in the development of one form of lace fringe.

Fig. 5 is a front view of the fragment of the lace edging of Fig. 4 showing an intermediate stage in the development of a lace fringe.

Fig. 6 is a front view of the lace fringe developed from the lace edging of Fig. 5.

Fig. 7 is a cross-section of the lace fringe taken along the line 7—7 of Fig. 6.

Fig. 8 is a plan view of a fragment of lace piece goods or a lace curtain showing a lace 15 edging developed from a modification of the weave of Fig. 2.

Figs. 9 and 10 are rear views of the lace edging of Fig. 8 showing successive intermediate stages in the development of the edging into a lace 20 fringe.

Fig. 11 is a rear view of a lace fringe developed from Figs. 8, 9 and 10.

Fig. 12 is a plan view of a fragment of another lace edging.

Fig. 13 is a rear view of the lace fringe developed from the fragment of lace edging of Fig. 12.

Fig. 14 is an enlarged plan view of a fragment of another lace edging.

Fig. 15 is a front view of a lace fringe developed from the fragment of lace edging of Fig. 14.

Fig. 16 is an enlarged plan view of a fragment of another lace edging.

Fig. 17 is a front view of the lace fringe developed from the fragment of lace edging of Fig. 15.

Fig. 18 is a plan view of a fragment of another lace edging.

Fig. 19 is a front view of the lace fringe developed from the lace edging of Fig. 18.

Figs. 20, 21 and 22 are separate plan views of fragments of a lace curtain, which when considered together, constitute successive stages in 45 the development of a lace fringe along the side edge or running edge of said lace curtain.

Like reference characters designate corresponding parts throughout the several figures of the drawings.

Any of the lace edgings shown in Figs. 1 to 5, 8 to 10, 12, 14, 16, or 18, may be woven separately as a lace strip, and thereafter folded to develop a lace fringe of appropriate character as shown generally in Figs. 6, 11, 13, 15, 17 or 19; 55

or any of the said lace edgings may be woven as an integral part of the pattern of a larger section of lace, such as a Nottingham lace curtain (Figs. 20 to 22), a lace table cloth, or lace 5 piece goods generally (Figs. 8 to 13). When woven as an integral part of a Nottingham lace curtain, the lace edging may subsequently be developed into a fringe located at the top and/or bottom of the curtain, or it may be developed 10 into a fringe located at the side or running edge of the curtain, as one or the other form of fringe may be desired by the weaver. In general therefore, and except where otherwise specified, the description which follows applies to lace 15 edgings formed either at the top and bottom, or at the side edge or edges of lace piece goods and Nottingham lace curtains, and to the lace fringes thereafter developed from said lace edgings, which fringes may likewise be formed either 20 at the top and/or bottom, or at the side edge or edges of lace piece goods or of Nottingham lace curtains or other lace articles. The lace edgings, lace piece goods, lace curtains, and other articles are woven as a repeat pattern upon a Nottingham 25 lace curtain machine, Levers machine, or the like.

Referring first to the simple pattern shown in Fig. 1, it will be assumed that the warp threads indicated by way of example at 20 to 26, have been 30 spaced equi-distantly apart so as to form uniform bars A, B, C, D, E, F, G, etc., throughout the lace edging. The weave of the pattern shown in Fig. 1 is made by withdrawing certain jacks or interceptors to form the clothing 31, 33, 35, 37 35 etc., and releasing certain other jacks or interceptors to make the open work 32, 34, 36, etc. For convenience in fabricating the edging a transverse band of clothing 30 is woven by withdrawing the jacks or interceptors and tying the 40 spool threads to the warp threads 20 to 26 inclusive to form a clothed band 30. When the lace edging forms the marginal edge of lace piece goods or of a lace curtain, the band of clothing 30 may either be used or omitted as desired. The 45 drops indicated at bars A, C, E, G, etc., are woven by withdrawing certain jacks or interceptors and tying the spool threads 31 to warp threads 20 and 21 to complete the clothed drop. In like manner the spool threads 33 are 50 tied to warp threads 22-23, and spool threads 35 to warp threads 24-25, to form a series of drops. The open work in bars B, D, F, etc., is made by releasing the corresponding jacks or interceptors. The length of the drops A, C, E, G, 55 etc., will vary according to the class of work and the desired length of finished fringe to be developed from said drops. The lace edging may be finished off in any preferred manner, as for example, by weaving a second transverse band of 60 clothing 40, which band may be a repeat of the band 30, to unite drops A, C, E, G, etc., together in spaced relation, thereby forming a lace edging substantially as shown in Fig. 1. Said lace edging may form the marginal edge of a larger piece 65 of lace as for example, a lace curtain, lace panel, lace table cloth, lace scarf, or other lace piece goods; or said lace edging may be woven for sale as a separate article. The marginal edge of the lace drops A, C, E, G, etc., may be finished off in any preferred manner to prevent 70 unravelling; when a band of clothing 40 is provided, unravelling may be prevented by (a) stitching or lockstitching the edging, or (b) by folding the band of clothing 40 upon itself along 75 a line 41, and stitching the formed fold (see

Figs. 4 and 5); the edging (Fig. 1) may then be folded between the bands of clothing 30 and 40 to bring the upper and lower half of each drop, A, C, E, G, etc., into optical registry, to complete the fringe, which is then retained in 5 position by stitching the free edges together, which in the specific construction shown in Fig. 1 could be accomplished by stitching transverse band 40 to transverse band 30. With the drops thus folded in optical registry, the number of 10 drops per running inch or per gauge in the finished fringe, will be equal to one-half the number of bars or points.

Fig. 2 illustrates a simple method of creating the optical illusion of appearing to form a finished fringe having twice as many drops as a fringe made as described for Fig. 1. This is accomplished by weaving and tying the spool threads 31, 33, 35 between their respective pairs of warp threads 20-21, 22-23, 24-25, for one- 15 half the length of the bars, A, C, E, G, and leaving the inner half of bars B, D, F, open work, as before; but in weaving the outer half of bars 20 A to G etc., the jacks or interceptors corresponding to bars A, C, E, G, etc., are released, and the 25 jacks or interceptors corresponding to bars B, D, F, etc., are withdrawn, thus moving the clothing 30 over one bar and tying spool threads 42, 44, 46 to their respective pairs of warp threads 21-22, 23-24, 25-26, thus in effect regrouping 30 the pairs of warp threads, and staggering the outer drops woven in bars B, D, F, etc., relative to the inner drops previously woven in bars A, C, E, G, etc. The outer drop (Fig. 2), like the drops of Fig. 1, may be reinforced at their outer 35 extremity in spaced relation by a tie-thread, which tie-thread may be extended to form a band of clothing 40 as before. The reinforcing tie-thread, or the band 40, may be treated in any preferred manner to prevent unravelling, and the 40 fringe may then be completed by folding the edging. Where, as illustrated (by way of example only) in Fig. 2, the edging is provided with transverse bands 30 and 40, the fringe may be completed by stitching said bands 30 and 40 45 together as before, thus forming a fringe presenting the optical illusion of twice as many drops per running inch (or per gauge) as the fringe of Fig. 1. By the cross-over of the spool threads from 31-33-35, to 42-44-46, the drops are 50 tied together across the bars A to G, in spaced relation to prevent the drops from curling up or becoming displaced. When the lace edging is 55 folded to form the finished fringe, the line of threads formed by the cross-over of the spool threads produces the optical illusion of a zig-zag line 53 (Figs. 8 to 11) along the tips of the drops defining the lace fringe.

In the modification shown in Figs. 3 the bars of clothing are formed in the same manner as 60 the bars of clothing in Fig. 2, but the drops are woven by clothing two adjacent bars A-B, E-F, leaving two bars (C-D) of open work, therebetween. In the outer half the clothing may be moved over two bars to form a drop 65 two bars wide at C-D, with open work two bars wide at A-B and E-F therebetween. In this case also the cross-over of the spool threads unites the drops in spaced relation across the bars A to G, etc. midway between the band of 70 clothing 30 and the band of clothing 40, thus tying the drops together thereby preventing them from curling up or becoming displaced; and the cross-over of the spool threads produces the optical illusion of a zig-zag line 53 extending along 75

the tips of the drops defining the lace fringe (see Figs. 8 to 11).

The simple weaves disclosed in Figs. 1, 2, and 3, are capable of endless variations. By employing a "two-in and one-out" weave, and by moving the clothing bars (between the clothing band 30 and clothing band 40) one or more bars, drops of varying widths and lengths may be produced; for example, the inner drops may be made narrower and/or longer than the outer drops, the outer drops may be made narrower and/or longer than the inner drops, or narrow drops alternating with wide drops in the inner half and wide drops alternating with narrow drops in the outer half, may be produced. Many striking ornamental fringe effects may be produced by the endless variations which will be obvious to those skilled in the art.

Figs. 4, 5, 6 and 7 illustrate successive steps in the manufacture of one form of drop fringe. After the warp threads 20 to 29, etc., inclusive have been clothed to form, by way of example, band 30, they may be drawn together and clothed to form an inner medallion 51. Emerging from medallion 51 the warp threads are pillared or grouped together in pairs 20—21, 22—23, 24—25, 26—27, 28—29, etc., by means of their associated spool threads 31, 33, 35, 37, 39, etc.; the open work at 32, 34, 36, 38 being formed 30 by releasing the corresponding jacks or interceptors in the manner previously described. Between the inner medallion 51 and the outer medallion 52 a line of tie-threads 50 extends across the bars to tie all of the drops together in spaced relation, in this case to form a series of groups of pillared warp threads diverging from inner medallion 51. Beyond the line of threads 50 the groups of pillared warp threads are extended to form a reverse repeat pattern of the drops of the inner half, warp threads 20—21, 22—23, 24—25, 26—27, 28—29, etc., converging and being clothed to form an outer medallion 52, the warp threads thereafter diverging a short distance and then further extended and clothed 45 to form a band of clothing 40. If the lace edging is woven as a separate article both edges will require treatment to prevent unravelling; but if the lace edging forms the marginal edge of a larger piece of lace, such as a lace curtain or table cloth, only the marginal edge (in Fig. 3 50 the band of clothing 40) will require treatment to prevent unravelling. One such mode of treatment is shown in Fig. 4, where the band of clothing 40 is folded upon itself (as along its 55 transverse median line 41) and the double ply thus formed (Fig. 5) is stitched by means of a line of stitches 48 traversing the band of clothing 40. The lace edging is now folded along the line of fold indicated by the line of threads 60 50, thus bringing the band 40, and the band 30, of clothing, into optical registry (Fig. 6), and the said bands of clothing are now secured together by a line of stitches 49 (see Figs. 6 and 7); or band 40 could be folded and stitched 65 to band 30 by the line of stitches 49, all in one operation. The line of tie-threads 50 interconnects the drops in spaced relation and thus prevents them from becoming curled up or otherwise displaced; the tie-threads 50 form an unbroken 70 line across the outer edge of the drop fringe to provide an ornamental finish for the edge of the lace fabric of which the fringe forms a part. If the lace edging shown in Figure 4 were not the marginal edge of a larger piece of lace, the 75 band of clothing 30 would require treatment to

prevent unravelling, and said lace edging could then be stitched to the marginal edge of a lace curtain, lace table cloth, or other goods, to form an ornamental drop fringe edging for said goods.

Figures 8, 9, 10 and 11 show successive stages 5 in the development of the lace edging of Fig. 8 into the lace fringe of Fig. 11. The pattern is a variation of that disclosed in Figure 2. The warp threads 20 to 26 etc., may pass through a band of clothing 30, then into the clothed groups 10 (22—21, 24—23, 25—26), of pillared warp threads with open work (32, 34, 36) therebetween to form the inner drops 31, 33, 35, etc., the clothing bars being thereafter moved over one bar and the warp threads (20 to 26 etc.) regrouped and then repillared to form a series of outer drops (42, 44, 46, etc.) which are aligned with the open work (32, 34, 36) in the inner half of the edging. The outer drops (42, 44, 46, etc.) which are staggered relative to the inner 20 series of drops (31, 33, 35, etc.) are connected to said inner series by the cross-over of the spool threads presenting the optical illusion of a zig-zag line of threads 53. When the transverse band of clothing 40 is employed it is treated to 25 prevent unravelling as by being folded along the line 47 (Figs. 8 and 9), and stitched to form a fast edge (Fig. 10). When the lace edging is not woven with a fast edge on the lace making machine, a fast edge may be provided by folding 30 the lace edging along a line indicated at 54—54 (Fig. 9), and the hem thus formed may be stitched with one or more lines of stitches 55 traversing the lace edging and lace piece goods (Fig. 10). The fringe is completed by folding 35 the lace edging along the line of fold indicated by the zig-zag line of threads 53 to produce the fringe shown in Figure 11, the fringe being held in place by one or more lines of stitches 56. The lace edging of Figure 8 from which the lace 40 fringe of Figure 11 is developed, may consist of the marginal edge of a lace curtain or other lace piece goods 57 (Fig. 8); or it may be woven as a separate article and thereafter folded and developed into a fringe while at the same time being applied to the edges of a section of lace or other goods.

Figures 12 and 13 show how another ornamental form of drop fringe (Fig. 13) may be developed from a lace edging (Fig. 12) forming 50 for example the marginal edge of a larger section of lace 58. Groups of pillared warp threads 60—61—62—63, 64—65—66—67, form an inner series of drops 70, 72, with open work 73, 75, therebetween; the groups of pillared warp 55 threads are then regrouped and repillared to form an outer series of drops 80, 82, which are positioned in alignment with the open work 73, 75, and in staggered relation to the drops 70, 72. The outer marginal edge is reinforced either 60 with a tie-thread or with a band of clothing 40, for securing drops 80, 82, etc., together in spaced relation, and said band may be treated to prevent unravelling in any preferred manner, as by folding, stitching, lockstitching, etc. If the fabric is not provided with a fast edge, it may be folded along a line 90—90 (Fig. 12), and then stitched with a line of stitches 91 (Fig. 13). By folding the lace edging along a line of fold indicated by the zig-zag line 92, the outer series 70 of drops 80, 82, etc., are positioned in the spaces between the inner series of drops 70, 72, etc., formed by the open work 73, 75, etc. The band of clothing 40 is thus brought into optical 75 registry with the band of clothing 30, said bands 75

being then secured together by a line of stitches 93. The zig-zag line of threads 92, formed by the regrouping and re-pillaring of the warp threads, acts as a line of tie-threads between the drops 70, 72, etc., and 80, 82, etc., thus providing an ornamental finish to the marginal edge of the curtain (Fig. 13), and at the same time preventing the drops from becoming curled up or displaced. In Figures 12 and 13 the drops 10 formed by the groups of pillared warp threads resemble elongated columns supporting medallions 84 and capitals 95.

Figs. 14 to 17 inclusive variously illustrate other suggested ways of ornamenting the drops, 15 with medallions and the like. In the variation shown in Figs. 14 and 15, a series of medallions 100—100 are woven between groups of drops 31—33—35—37, in the inner half of the lace edging. By shifting the clothing one bar, the 20 warp threads 20—21—22—23—24—25—26—27—28—29 are regrouped and repillared as indicated by the zig-zag line 92, to weave a series of drops 42—44—46 etc., in the outer half of the lace edging in staggered relation to the drops 25 31—33—35—37 of the inner half of said edging and in alignment with the open network 32—34—36—38 between said inner series of drops; so that when the lace edging is folded along a line of fold indicated generally by the 30 zig-zag line 92 the outer series of drops 42—44—46 etc., will be aligned in the spaces between the inner series of drops 31—33—35—37—39 defined by the open network 32—34—36—38 to develop a lace fringe. To retain the fringe in proper position the clothed bands 30 and 40 may be stitched together by one or more transverse lines of 35 stitches 93 (Fig. 15), the zig-zag line of threads 92 forms an ornamental finish for the outer edge of the fringe and at the same time prevents the drops from becoming curled up or displaced.

The lace edging illustrated in Figs. 16 and 17 may be formed in like manner by weaving clothing at a plurality of spaced points 101—103 to 40 form a border for an open network having clothing woven therein in the form of a series of medallions 102—102, simulating flowers or other objects in silhouette, tied to the warp threads 20—21—22—23—24—25—26—27—28—29 etc. The fringe (Fig. 17) is completed as 45 previously described in any preferred manner.

The number of warp threads grouped or pillared together (as at 70—72, 80—82, Fig. 12) may be varied, dependent upon the form of drop desired; or the drops may be made in skeleton or without any clothing associated with the warp threads. The drops may also be woven on the marginal edge of a curtain or lace article without employing the band of clothing 30. In other 50 words, the ornamentation of the drops may be endlessly multiplied to weave an almost infinite variety of lace fringes on lace making machines, either as a part of a lace curtain or other lace fabric, or as a separate lace edging 55 adapted to be secured to piece goods by a stitching operation. When the fringe is woven as an integral part of a lace article the fringe will conform to the color and texture of the article, and both waste in trimming and expense due to 60 separate handling, are avoided.

Instead of weaving a line of spool threads 50 across the transverse median line of the drops as disclosed generally in Figs. 4, 5, and 6, or across the transverse zig-zag line 53 (Figs. 5 to 75 11), a plurality of spaced lines of tie-threads

50, 50' (Fig. 18), may be woven between the drops 31, 33, 35, so that if the drops are folded midway between the transverse bands 30 and 40, a lace fringe having the inner halves of the drops in optical registry with their corresponding outer 5 halves, and the line of tie-threads 50 in optical registry with the lines of tie-threads 50' but with the tips of the drops free, to present a broken line, may be developed substantially as shown in Fig. 19. The tie-threads 50, 50' may be woven between the drops 31, 33, 35 at any intermediate point or points as preferred, Fig. 18 being one weave or pattern.

Figs. 20 to 22 inclusive variously illustrate how a lace edging substantially as shown in Fig. 18 15 may be woven as an integral part of the pattern of a Nottingham lace curtain. In this example, the lace fringe is to be formed along the side or running edge of the curtain 57 (Fig. 20), and the curtain is accordingly woven so that its length 20 extends across the width of the loom rather than lengthwise thereof. By this arrangement the warp threads 20 to 26 etc., extend across the width of the body 57 of the curtain, rather than lengthwise thereof according to the accepted 25 practice in weaving Nottingham lace curtains; and the spool threads extend lengthwise of the curtain, rather than across the width of the body 57 thereof according to the accepted practice. The lace edging of Fig. 18 thus in effect 30 forms the side edge (or running edge) of the curtain body 57 (Fig. 20). The band 40 now forms a marginal edge band (Fig. 20), and it may be finished off to prevent unravelling by folding it at 47, and then stitching the folded 35 plies with a running line of stitches 48 (Fig. 21). The lace fringe may now be developed and the curtain 57 completed by folding the edging as along the median line of the drops 31, 33, 35 etc., to bring clothed bands 30 and 40 into cooperative 40 registry and lines of tie-threads 50 and 50' into optical registry, and by then stitching the bands 30 and 40 together by a line of stitches 56 to retain the lace fringe in its final position (Fig. 22). The fringe thus developed runs lengthwise of the 45 body 57 of the curtain (Fig. 22), and forms the side edge (or running edge) of the finished article. When a curtain having a fringe fabricated along its running edge as illustrated in 50 Figs. 20, 21, and 22, is suspended from a curtain rod, tie backs may be employed thus giving the draped curtain a most attractive ornamental effect. Any of the various forms of lace edging disclosed in the several figures of the drawings and any variation of any of them, may be substituted for the lace edging forming the side edge or running edge of the body 57 of the curtain 55 shown in Figs. 20, 21, and 22.

Similarly by weaving the curtain lengthwise of the loom, so that the warp threads 20 to 26 extend lengthwise of the body of the curtain instead of crosswise thereof, the lace edgings shown in the various figures of the drawings, or any of them, may be developed into a lace fringe extending across the top or bottom, or across the 60 top and bottom of the body of a curtain 57, instead of along the side edge or running edge of the body 57 of the curtain as shown in Figs. 20 to 22.

A lace fringe embodying the invention may be 70 woven as an integral part of a valance, which valance may either be a separate lace article, or may be woven as an extension top for a Nottingham lace curtain. In either case the lace fringe will extend from the lower edge of the valance when 75

the latter is suspended in hung position. The optical illusion of the zig-zag lines indicated at 53 (Figs. 8 to 11) and 92 (Figs. 12 to 17), is produced by moving the clothing over one or more bars in the operation of staggering the outer drops relative to the inner drops and regrouping and re-pillaring the warp threads.

What is claimed is:

1. The method of manufacturing a lace curtain which consists in weaving the length of the curtain at right angles to the warp threads so that the warp threads extend from side edge to side edge of the body of the curtain, extending the warp threads beyond the normal finishing line of the side edge of the body of the curtain, weaving a series of elongated lace drops of close structure alternating with open work between the warp threads as thus extended to form a lace edging extending along the side edge of the body of the curtain and beyond the normal finishing line thereof, folding said lace edging back substantially along the normal finishing line of the side edge of the body of the curtain to transform said lace drop into a series of loops defining a lace fringe projecting beyond the said normal finishing line, and stitching the folded plies of the lace edging together to retain the lace fringe in position and prevent the lace loops from unravelling.
2. The method of manufacturing a lace curtain which consists in weaving the body of the curtain with its length at right angles to the warp threads so that the warp threads extend across the body of the curtain from side edge to side edge thereof, extending the warp threads beyond the normal finishing line of the side edge of the curtain body, weaving a series of lace drops of close structure alternating with open work between the warp threads as thus extended to form a lace edging parallelling the side edge of the body of the curtain and beyond the normal finishing line thereof, joining the drops together in spaced relation, treating the lace edging to prevent unravelling thereof, folding said lace edging back substantially along the normal finishing line of the said side edge to transform said lace drops into a series of loops defining a lace fringe projecting laterally outwards beyond the normal finishing line of the said side edge, and stitching the folded plies of lace edging together to retain the lace fringe in position.
3. The method of manufacturing a lace curtain which consists in weaving the body of the curtain with its length at right angles to the warp threads, extending the warp threads beyond the normal finishing line of the side edge of the curtain body, weaving clothing between spaced groups of said extended warp threads for a certain pre-determined distance to form a series of elongated lace drops of close structure alternating with open work, joining the lace drops together in spaced relation, in like manner weaving a second series of elongated lace drops between said warp threads for a distance substantially equal in length to said first series, treating the ends of said second series of lace drops to prevent unraveling, folding said elongated drops back substantially along the normal finishing line of the side edge of the body of the curtain to transform said lace drops into a series of loops defining a lace fringe projecting laterally outwards beyond the normal finishing line of the side edge of the curtain, and stitching the folded plies together to retain the lace fringe in position.
4. The method of manufacturing a lace curtain which consists in weaving the body of the curtain with its length at right angles to the warp threads, extending the warp threads beyond the normal finishing line of the side edge of the curtain body, weaving clothing between predetermined spaced groups of said warp threads for a distance substantially equal to the length of a lace fringe to be formed in part by the series of elongated lace drops of close structure with open work between said drops thus woven, regrouping the warp threads into other spaced groups, extending the clothing between said spaced groups of warp threads as thus re-grouped for substantially the same distance as before to weave a second series of elongated lace drops of close structure with open work between them, said second series of drops being in alignment with the open work between said first series of drops and the open work between said second series of drops being in alignment with said lace drops of said first series, reinforcing the ends of said second series of lace drops, treating the reinforced ends to prevent unravelling, folding said elongated drops back to the approximate normal finishing line of the side edge of the body of the curtain to align the lace drops of each series in the spaces defined by the open work between the lace drops of the adjacent series to form a looped fringe displaying all of the drops in each series, and stitching the folded plies together to secure said lace fringe in position.
5. The method of manufacturing a lace curtain with an integral lace fringe along the length of the side edge thereof which consists in weaving the body of the curtain with the warp threads running across the width thereof, extending said warp threads beyond the normal finishing side edge of the curtain, weaving clothing between certain of said warp threads as thus extended for a distance greater than the ultimate length of lace fringe desired, to form a series of lace drops with open work between them, and stitching the ends of the lace drops to the curtain body adjacent the normal finishing side edge thereof to form a looped lace fringe, to retain said fringe in position, and to prevent it from unravelling.
6. A lace curtain having the warp threads running across the curtain body substantially at right angles to the length of the curtain body, said warp threads extending beyond the normal finishing side edge of the curtain body, clothing woven between certain of said warp threads as thus extended to form a series of elongated lace drops with open work between them projecting laterally from the side edge of the curtain, said elongated drops being folded back against the normal finishing side edge of the curtain to change said drops into a series of lace loops defining a fringe of lace, and a line of stitches traversing the free edges of the folded drops and the marginal edge of the curtain body to retain the lace fringe in position and prevent it from unravelling.
7. A lace curtain having the warp threads running in a direction substantially at right angles to the length of the curtain body and extending beyond the normal finishing side edge thereof, clothing woven between certain of said warp threads as thus extended to form a series of elongated lace drops with open work between them projecting laterally from the side edge of the curtain, tie-threads extending between intermediate sections of said elongated drops, said elongated drops being folded back against the normal

finishing side edge of the curtain to change said drops into a series of interconnected lace loops defining a fringe of lace, and a line of stitches traversing the free edges of the folded drops and 5 the marginal edge of the curtain body to retain the lace fringe in position and prevent it from unravelling.

8. A lace curtain having a lace fringe projecting laterally outwards from the normal side edge 10 of the curtain, said curtain having its warp threads running at right angles to the length of the curtain body, said warp threads extending beyond the normal finishing side edge of the curtain body, clothing woven between certain pre-determined groups of said warp threads as thus 15 extended to form a first series of elongated lace drops with open work between them, clothing woven between certain other pre-determined groups of said warp threads as further extended 20 to form a second series of elongated lace drops with open work between them in extension of said first series, the lace drops of each series being positioned in alignment with the open work between the lace drops of the other series, 25 said drops being folded along the line of merger of the first and second series to align the lace drops of each series in the spaces defined by the open work between the lace drops of the adjacent series to form the lace fringe, and one or more 30 lines of stitches traversing the free edges of said

second series of drops and the side edge of the curtain body to retain the fringe in position and prevent unravelling thereof.

9. A lace curtain having a lace fringe edging merging with the body of the curtain and in extension thereof, said line of merger defining the line of the normally finished edge of the curtain body, said lace fringe comprising warp threads extending beyond the normally finished edge of the curtain body, clothing woven between certain pre-determined groups of said warp threads as thus 5 extended to form an inner row of elongated lace drops with open work between them, said inner row of drops being interconnected in spaced relation, said warp threads extending beyond the ends of said inner row of drops, clothing woven between certain pre-determined groups of 10 said warp threads as thus further extended to form an outer row of elongated lace drops with open work between them, said outer row of drops 15 also being interconnected in spaced relation, said edging being folded along a line parallelling the normally finished edge of the curtain body and between said inner and outer row of drops to bring said rows of drops into cooperative registry 20 to form said lace fringe, and means for uniting the folded plies of fabric together to retain the formed fringe in position and prevent unravelling 25 thereof.
